CLAIM

The ornamental design for an air fry oven, as shown and described.

DESCRIPTION

FIG. 1 is a top, front, and right side perspective view of an air fry oven, showing our new design;

FIG. 2 a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

The broken lines are shown for the purpose of illustrating parts of the article that form no part of the claim.
